NEEDLE AND THE LIKE

Application filed June 18, 1928. Serial No. 286,207.

This invention relates to needles, and more particularly a needle adapted for repairing runs or ravelings in stockings and other knitted fabrics.

5 Needles now in use for such purposes ordinarily have a body member with a hook formed at one end and a latch member pivoted to the body member, the free end of the latch member being adapted to fly up and down as the needle is moved forward and backward through the fabric being repaired, thus opening and closing the hook as may be necessary to perform the repair work. The problem with such needles is to cause 10 the free end of the latch to be raised quickly during the downward movement of the hook member, so that the point of the latch will not catch in the fabric and delay the operation or injure the fabric.

15 My needle has no pivoted member and consequently does not encounter the difficulty above pointed out. My needle has an elongated body member, at one end of which a hook is formed, said body member also having a longitudinally disposed opening in which a latch member slides back and forth for the purpose of opening and closing the hook. There are also suitable means for limiting the distance through which the sliding member can move in longitudinal direction away from the hook and also means to prevent or limit the amount of the turning motion of the sliding member.

20 One of the numerous advantages of this new type of needle is its cheapness and simplicity of construction. Another advantage is the fact that, by reason of its compact construction, it is necessary to move the needle only a relatively short distance backward and forward through the fabric in order to reknit or crochet the rungs of the ladder constituting the runner portion of the stocking and thus make the repair, whereas, with pivoted-latch needles heretofore used, a much 25 longer movement of the needle is necessary

to accomplish this purpose. This shorter movement of my needle results in greater speed and ease of operation than has heretofore been possible.

My needle also has the advantage, (because 50 of its simplicity of construction and the absence of the awkward swinging latch of the old type of needle) of being practically free from the possibility of damage during its operation and also while it is lying around 55 in a shop when not in use.

In the accompanying drawings Fig. 1 is an enlarged side elevation, partly in section, of my needle in its preferred form.

Fig. 2 is a plan view.

Fig. 3 is a side elevation of the body member of the needle.

Fig. 4 is a side elevation of the sliding latch member of the needle.

Fig. 5 is a perspective view of the beveled 65 end portion of the sliding latch.

Fig. 6 is an enlarged view, partly in section, of a somewhat modified form of the needle.

Fig. 7 is an enlarged view, partly in section, of a further modified form of the needle.

Fig. 8 is a still further modified form of the needle.

Fig. 9 is a view of the rear end of the needle shown in Fig. 2 taken on the line $\alpha-\alpha$. 75

Fig. 10 is an enlarged view of fabric containing a run or raveling of the kind for the reknitting or crocheting of which my needle is primarily designed.

The preferred form of my needle consists 80 of the body member 1, the sliding latch member 2 and the spring-carrying member 3. For convenience in operation the needle may be mounted in a handle 4. The needle in this form includes a tube, and a rod adapted to 85 fit slidably in said tube, there being located at the rear of the sliding rod, or latch, a rigidly held member which carries a spring portion 5 adapted to bear against a longitudinally disposed surface formed in the rear 90

portion of the sliding latch member; said spring acts to prevent the rotation of the latch member and also frictionally contacts the latch member in such manner as to prevent the latch from closing the hook 6 until 5 the latch is moved by a thread in the manner hereinafter described. The spring-carrying member also has a shoulder 7 adapted to stop the rearward movement of the latch member 10 at the desired point. The spring-carrying member is rigidly fixed in the rear end of the body member, preferably by forcing the side walls of the body member against the sides of the rear end of the spring-carrying member as indicated at 8 and also as shown 15 in Fig. 9. This method of fastening the spring-carrying member in the needle is desirable because it can be quickly accomplished when the different parts of the needle are in place by putting the end of the needle between the jaws of a vise and upsetting the 20 end of the body member as shown in Fig. 9. Moreover, the upset portion of the body member can be easily restored to normal substantially round condition by applying a vise to 25 the oblong portions of the end thus releasing the pressure on the end of the spring-carrying member and permitting the said member as well as the sliding latch member to be removed from the body member for the purpose 30 of making any necessary repairs or substitution of parts.

The front end of the sliding latch member is beveled upwardly and rearwardly at 9, 35 said beveled face having an opening 10 in the upper portion thereof.

The latch slants downwardly and rearwardly at 11 and then extends rearwardly at 12 to the point where the shoulder 13 is formed. The rear portion of the latch is 40 cut away to form the surface 14 against which the spring 5 bears for the purpose herein elsewhere stated.

The needle, when properly assembled, 45 functions in the following manner. The fabric to be repaired is first placed under a slight tension, preferably being held over a hollow cylindrical vessel of substantial depth. The hook end of the needle is then 50 forced into the fabric to be repaired at 15, just back of one of the last loops of the run or raveling, and the tension on the fabric is then somewhat increased. As the needle is pushed downwardly through the fabric the 55 loop 15 slips up over the hook and also over the top of the beveled portion 9 and along the face 12 until it encounters the shoulder 13 and closes over the body member and latch member at that point, this movement 60 of the loop serving to open the hook. At the same time the thread 16 straightens out to form part of the run. The spring 5 by frictionally engaging the rear end of the latch at 14 prevents the latch from prematurely closing 65 the hook at this stage of the operation when

the point of the hook 6 will be below and beyond the straightened cross thread 16, and as the upward movement of the needle starts, the hook 6 picks up the thread 16, and the loop 15 (which, as above stated, incloses the body 70 member and latch member below the shoulder 13) slides back over the surface 12 encounters the beveled portion 11 and forces the latch member downwardly so that the point of the hook enters the opening 10 and closes the hook. The loop 15 slides downwardly over the ridge formed by beveled portions 11 and 9 and over the hook 6, leaving the thread 16 in the hook portion of the needle to form a new loop. The downward and upward 75 movements of the needle are then repeated. On each such downward movement the loop lying in the hook slips up over the beveled portion 9 and opens the hook as the point of the hook passes below the next adjacent cross thread; and on each upward movement of the needle the hook grasps the adjacent cross thread, and the loop contacts the beveled 80 face 11, closes the hook and slides over the top of said beveled face and over the hook 6, 85 leaving the cross thread in the hook to form a new loop. Thus each thread of the ladder constituting the run is successively picked up by the hook and formed by the needle into a new loop as the needle proceeds along the 90 ladder to the end of the run.

A tacking operation with an ordinary needle and thread is then resorted to, such 95 needle and thread being used to fasten or tie the last loop (brought to this point by the 100 repairinig needle herein described) so as to prevent a recurrence of the run. Those skilled in the art of repairing such fabrics are familiar with the so-called "tacking" operation and in many instances are able to 105 close the original break in the fabric in such manner as to constitute a substantially invisible repair. In is therefore unnecessary here to describe this tacking operation. Moreover the purpose of my new needle is 110 not to do this tacking work, (which can best be done by employment of an ordinary sewing needle and thread) but to repair the "run", however long or wide it may be.

While my needle is preferably made in the 115 manner above stated, it may also be made in a variety of other forms such as those shown in Figs. 6, 7 and 8. In Fig. 6 the body member is designated as 17 the latch member as 18 and the means for preventing undue rearward movement and turning movement 120 as 19. 20 is the hook. 21 is an upwardly and rearwardly extending beveled face having the opening 22 therein. 23 is a downwardly and rearwardly extending beveled 125 face which is followed by the surface 24 and the shoulder 25. The body member 17 has a cutaway portion 26 and a shoulder 27. It also has a notch 28 adapted to receive a thread or elastic band 29 which bears upon 130

the upper surface of the shuttle member adjacent the notch 28 and makes a frictional contact on said shuttle member which acts to prevent said member from prematurely closing the hook as the loop of thread slides 5 downwardly along the surface 24 during the upward movement of the needle through the fabric being repaired. 30 is a cutaway portion of the rear end of the shuttle adapted to coact with part 21 to prevent undue turning 10 movement of the shuttle member.

In Fig. 7 the spring 22 attached to body member 23 extends through opening 24 in said body member and contacts the cutaway 15 portion of shuttle 25' at 26 serving to prevent undue rotation of the shuttle member and also frictionally bearing against the shuttle member so as to prevent premature closing of the hook during the operation of 20 the needle. The rear end of the shuttle is pointed at 27 to bear against the closed rear end of the body member at 28 and thus restrict rearward movement of the latch. 29' 25 is the hook. 30 and 31 are beveled portions of the latch by means of which the latch is opened and closed by a thread. 32 is an opening for the reception of the point of the hook.

In Fig. 8 there is a spring 33 set in a cut- 30 away portion 34 of shuttle 35, said spring frictionally contacting the inner surface of the body member at 36 to prevent premature closing of the latch during the operation of the needle. The rearward movement and the 35 turning movement of the latch are restrained by the end piece 37 and coacting rear member 38 of the shuttle. 39 is the hook; 40 and 41 are beveled faces adapted to coact with a thread to open and close the hook when the 40 needle is being operated for the purpose of repairing a run.

In order that a needle of the character herein described may be operated successfully in the class of work for which it is designed, it is important that the shuttle member fit in the body member in such manner that the shuttle will move freely back and forth in its channel. To obtain satisfactory results the shuttle should be 50 fitted in the body member so that it will normally move of its own weight back and forth in its channel when the needle is in an upright position and is then turned so that first one end and then the other extends 55 upwardly. While it is necessary to have the needle adjusted so that the shuttle and body member will constitute a loosely sliding fit with reference to each other, it is also necessary, when the needle is held in an upright 60 position for the purpose of repairing the fabric, that the shuttle be restrained from closing the hook during the upward movement of the needle while the loop of thread slides downwardly over the surface 12 until 65 it contacts the beveled face 11. This purpose

is accomplished in my present invention by devices for causing friction at another part of the needle which will be slightly greater than the friction of the loop against the surface 12. In the preferred form of my device 70 the spring 5 is employed for this purpose. In form of device shown in Fig. 6 this purpose is accomplished by means of a thread or an elastic band which surrounds the needle and bears against the shuttle at 28, 75 and in Figs. 7 and 8 springs are used for this purpose. In each of these devices the amount of the friction may be adjusted as desired by regulating the tension of the means employed against the surface in connection with which it operates. 80

While the different forms of devices illustrated all employ a closed tube with an interior rod acting as a shuttle, it is obvious that the body of the needle might consist of a member comprising a channeled portion in which the sliding latch is held and its longitudinal and rotary movement limited by rivets or other suitable means, a feature of my present invention consisting in the providing of regulatable frictional means for preventing the premature closing of the hook during the operation of the needle, whether this purpose be accomplished by the use of 90 a spring, an elastic band or thread, by flexing the body member or the shuttle, or by any other means whatsoever. 95

The term "regulatable frictional means," as employed in the next preceding paragraph, is intended to refer to frictional means which can be increased or diminished as may be necessary. Each of the frictional means herein shown and described can be so regulated. The friction of the means shown in Figs. 6 and 7 can be regulated without disassembling the needles since such means are located on the outside of the needles. To increase or diminish the friction in the type of needle shown in Fig. 6 it is only necessary to tighten or loosen the band or thread 29; 100 and the friction may be increased or diminished in the type of needle shown in Fig. 7 by flexing to a greater or less extent the spring 22 or by replacing the spring with one having greater or less tensional strength. The friction can be increased or diminished in the preferred form of my needle by removing the spring-carrying member 3 (it being understood that the spring 5 may be integral with or detachable from member 3) 110 in the manner hereinabove stated and flexing the spring to a greater or less extent as may be desired or the spring (either with or without the carrying member 3) may be replaced 115 with one of greater or less tensional strength. To increase or decrease the friction in the type of needle shown in Fig. 8 it is necessary to disassemble the needle; however this can readily be done by removing the end piece 37 (which is clamped or otherwise tightly 120

held in place) and taking out the shuttle member, when the tension of the spring can be increased or diminished by flexing it to a greater or less extent, or the desired purpose can be accomplished by substituting a spring of greater or less tensional strength.

In order that the needle may operate properly in repairing a run it is essential that the friction caused by the means employed for this purpose shall be slightly greater than the friction caused by the loop on the shuttle as it slides downwardly along the surface 12, however it must permit the downward movement of the latch to close the hook as the loop bears against the beveled face 11. If the friction is too strong the descending loop will enter the open hook instead of sliding over it, and if the friction is too weak the ascending hook will be closed prematurely, with the result that the hook will fail to pick up the adjacent cross thread and the descending loop will slip over the hook and cause a "drop thread" with a consequent extension of the run.

The adjustment of the latch in the body member with a degree of tension one against the other sufficient to answer the purpose is extremely difficult since such friction steadily decreases with the wear caused by the backward and forward movement of the latch in its channel and such friction could not be adjusted to meet the delicate requirements of successful operation of the needle unless by a slight flexing of the body member or the shuttle as above suggested; consequently independent frictional means, including those of a flexible or resilient nature, are preferably employed. The means herein shown and described have proven efficient for this purpose.

What I claim is—

1. In a sliding latch needle for repairing runs a shank member terminating in a hook; a latch member adapted to be moved by a thread back and forth along said shank member to open and close said hook, said latch member having at one end thereof a beveled face with an opening therein adapted to receive the point of the hook; and frictional means adapted to prevent the premature closing of the hook when the needle is moved longitudinally through the fabric being repaired.

2. A needle as described in claim 1, with the additional feature that the frictional means thereof for preventing the premature closing of the hook forms part of the needle.

3. A needle as described in claim 1, with the additional feature that the frictional means thereof for preventing the premature closing of the hook is of a resilient nature.

4. A needle as described in claim 1 with the additional feature that the frictional means thereof for preventing the premature closing of the hook is adjustable.

5. A needle for repairing runs in knitted fabrics comprising a shank member terminating in a hook and an operatively connected sliding latch member, the end of said latch member having an upwardly and rearwardly slanting surface with an opening therein adapted to receive the point of said hook and adjacent to said surface a downwardly and rearwardly slanting surface forming on the latch a projection whereby a loop of thread may be retained on the needle until the hook picks up an adjacent cross thread of the run being repaired and the latch closes the hook on said thread preparatory to pulling said thread through said loop to form a new loop.

6. A needle having a plurality of members including a hook and means for opening and closing said hook, two of said members being in sliding relation to each other and comprising means adapting the needle for repairing runs in knitted fabrics including a shoulder upon one of said members for restricting the longitudinal movement of a thread along the member in a direction away from said hook.

7. A needle having a plurality of members including a hook and means for opening and closing said hook adapted to be operated by a thread, two of said members being in sliding relation to each other and comprising means adapting the needle for repairing runs in knitted fabrics including a shoulder upon one of said members for restricting the longitudinal movement of a thread along the member in a direction away from said hook.

8. A needle having a shank member terminating in a hook and a latch member for opening and closing said hook adapted to be operated by a thread, said members being in sliding relation to each other and comprising means adapting the needle for repairing runs in knitted fabrics including a depression terminating in a shoulder upon the latch member for restricting the longitudinal movement of a thread along that member in a direction away from said hook.

9. A needle adapted to be moved with a reciprocating motion through a knitted fabric for repairing runs or ravel therein, comprising a plurality of members containing means for co-acting with a thread of the run or ravel to limit the extreme positions of the needle in its reciprocating motion.

10. A needle adapted to be moved with a reciprocating motion through a knitted fabric for repairing runs or ravel therein, comprising a shank member terminating in a hook and a latch member, said members containing means for co-acting with a thread of the run or ravel to limit the extreme positions of the needle in its reciprocating motion, and one of said members containing means for co-acting with a thread of the run or ravel to bring said latch member in opened and closed relation said hook.

11. A needle adapted to be moved with a reciprocating motion through a knitted fabric for repairing runs or ravels therein, comprising a shank member terminating in a hook and a latch member, said members containing means including a shoulder for co-acting with a thread of the run or ravel to limit the extreme positions of the needle in its reciprocating motion, and the latch member containing means including a beveled face and a depression in its upper surface for co-acting with a thread of the run or ravel to bring said latch member in opened and closed relation with said hook. 70
12. A needle adapted to be moved with a reciprocating motion through a knitted fabric for repairing runs or ravels therein, comprising a shank member terminating in a hook and a latch member, said members being in sliding relation to each other and one of said members containing means including a shoulder for co-acting with a thread of the run or ravel to limit the extreme position of the needle in its reciprocating motion below the fabric, and the latch member containing a beveled face and a depression in its upper surface for co-acting with a thread of the run or ravel to bring said latch member in opened and closed relation with said hook. 75
13. A needle adapted to be moved with a reciprocating motion through a knitted fabric for repairing runs or ravels therein, comprising a shank member terminating in a hook and a latch member, said members being in sliding relation to each other and containing means for co-acting with a thread of the run or ravel to limit the extreme positions of the needle in its reciprocating motion, and the latch member containing means for co-acting with a thread of the run or ravel to move said latch member in opened and closed relation with said hook at predetermined times as said needle is respectively moved downwardly and upwardly through the fabric. 80
14. A needle adapted to be moved with a reciprocating motion through a knitted fabric for repairing runs or ravels therein, comprising a shank member terminating in a hook and a latch member, said members being in sliding relation to each other, and the latch member containing means including a beveled face and a depression in its upper surface terminating in a shoulder for co-acting with a thread of the run or ravel to limit the extreme position of the needle in its reciprocating motion below the fabric and to move said latch member in opened and closed relation with said hook at predetermined times as said needle is respectively moved downwardly and upwardly through the fabric. 85
15. A needle adapted to be moved with a reciprocating motion through a knitted fabric for repairing runs or ravels therein, comprising a shank member terminating in a hook and a latch member, said members being in sliding relation to each other, and the latch member containing means for co-acting with a thread of the run or ravel to limit the needle in its reciprocating motion below the fabric only at the predetermined time of the latch member being in opened relation with said hook. 90
16. A needle adapted to be moved with a reciprocating motion through a knitted fabric for repairing runs or ravels therein, comprising a shank member terminating in a hook, a latch member and frictional means, said members being in sliding relation to each other, and one of said members containing a shoulder for co-acting with a thread of the run or ravel to limit the extreme position of the needle in its reciprocating motion below the fabric, the latch member containing means for co-acting with a thread of the run or ravel to move said latch member in opened and closed relation with said hook, said frictional means being adapted to prevent the premature closing of the hook when the needle is moved through the fabric being repaired. 95
17. A needle adapted to be moved with a reciprocating motion through a knitted fabric for repairing runs or ravels therein, comprising a shank member terminating in a hook and a latch member, said members being in sliding relation to each other, and the latch member containing a beveled face and a depression in its upper surface whereby a loop of thread may be retained thereon until said loop moves the latch to a closed position with relation to the hook preparatory to pulling said cross-thread enclosed in the hook through said loop to form a new loop. 100
18. A needle adapted to be moved with a reciprocating motion through a knitted fabric for repairing runs or ravels therein, comprising a shank member terminating in a hook and a latch member, said members being in sliding relation to each other, and the latch member having a beveled face and a depression in its upper surface whereby a loop of thread may be retained thereon until the hook picks up an adjacent cross-thread of the run being repaired and pulls said cross-thread into a new loop, and one of said members containing a shoulder for co-acting with the loop of thread to limit the movement of the needle in its reciprocating motion below the fabric. 105
19. A needle adapted to be moved with a reciprocating motion through a knitted fabric for repairing runs or ravels therein, comprising a shank member terminating in a hook and a latch member, said members being in sliding relation to each other, the latch 110
20. A needle adapted to be moved with a reciprocating motion through a knitted fabric for repairing runs or ravels therein, comprising a shank member terminating in a hook and a latch member, said members being in sliding relation to each other, and the latch member containing means for co-acting with a thread of the run or ravel to limit the needle in its reciprocating motion below the fabric only at the predetermined time of the latch member being in opened relation with said hook. 115
21. A needle adapted to be moved with a reciprocating motion through a knitted fabric for repairing runs or ravels therein, comprising a shank member terminating in a hook and a latch member, said members being in sliding relation to each other, and the latch member containing means for co-acting with a thread of the run or ravel to move said latch member in opened and closed relation with said hook, said frictional means being adapted to prevent the premature closing of the hook when the needle is moved through the fabric being repaired. 120
22. A needle adapted to be moved with a reciprocating motion through a knitted fabric for repairing runs or ravels therein, comprising a shank member terminating in a hook and a latch member, said members being in sliding relation to each other, and the latch member containing means for co-acting with a thread of the run or ravel to limit the needle in its reciprocating motion below the fabric only at the predetermined time of the latch member being in opened relation with said hook. 125

member containing a beveled face and a depression in its upper surface for co-acting with a loop of thread whereby said latch member may be moved to opened relation with said hook and said loop of thread may be retained thereon until the hook picks up an adjacent cross-thread of the run being repaired and pulls said cross-thread into a new loop, said depression terminating at one end in a shoulder for co-acting with the loop of thread to limit the movement of the needle in its reciprocating motion below the fabric, and terminating at the other end in a sloping portion whereby said latch member is moved to closed position by said retained loop upon reversing the movement of the needle through the fabric and the retained loop is cast off over the hook, and the cross-thread, enclosed in the hook by the latch, is pulled into a new loop.

20. The method of repairing runs or ravels in fabrics which consists in stretching the fabric, inserting into a loop formed in the run or ravel a needle comprising a shank member terminating in a hook portion and a sliding latch member, one of said members containing a shoulder and the latch member having a beveled face and a depression in its upper surface, continuing the movement of said needle on through the fabric until the loop has opened the latch by sliding upwardly over the beveled face and limits the downward movement of said needle by sliding into the depression and against said shoulder, catching the next forward thread in the hook while the loop is being pulled over the latch causing the latch to co-act with the hook portion in closed relation and the loop to be cast off over the end of the hook portion, the thread caught in the hook limiting the movement of upward travel of the needle and forming a new loop taking the place of the first described loop then reinserting the needle into the fabric as before and repeating the operation until the run or ravel has been repaired.

21. The method of repairing runs or ravels in knitted fabrics which consists in stretching the fabric, inserting into the loop formed in the run or ravel a needle comprising a shank member terminating in a hook portion and a sliding latch member, the latter having a beveled face and a depression in its upper surface terminating in a shoulder, continuing the movement of said needle on through the fabric until the loop has opened the latch by sliding upwardly over the beveled surface and limits the downward movement of said needle by sliding into the depression and against said shoulder, then reversing the movement of the needle through the fabric catching the next forward thread in the hook while the loop is being pulled over the latch causing the latch to co-act with the hook portion in closed relation and the

loop to be cast off over the end of the hook portion, the thread caught in the hook limiting the movement of upward travel of the needle and forming a new loop taking the place of the first described loop, then reinserting the needle into the fabric as before and repeating the operation until the run or ravel has been repaired.

In testimony whereof I have affixed my signature.

STANLEY W. FINCH.
